(57) **CLAIM**

The ornamental design for a lighting fixture, as shown and described.

DESCRIPTION

FIG. 1 is a fragmentary view showing one end and a portion of the bottom of a first embodiment of the new design of a lighting fixture;

FIG. 2 is a fragmentary perspective view showing one end, a portion of one side and a portion of the bottom of the lighting fixture of FIG. 1;

FIG. 3 is a longitudinal elevational view, showing one side of the lighting fixture of FIG. 1;

FIG. 4 is a longitudinal elevational view, slightly tilted along its longitudinal axis and showing an opposite side and the top of the lighting fixture of FIG. 1;

FIG. 5 is a fragmentary perspective view showing one end, a portion of the bottom and a portion of one side of a second embodiment of the new design of a lighting fixture;

FIG. 6 is a longitudinal elevational view, slightly tilted along its longitudinal axis, and showing one side and the bottom of the lighting fixture of FIG. 5; and,

FIG. 7 is a fragmentary enlarged end view, slightly tilted and showing from below, a baffle configuration used in the lighting fixture of FIG. 5.
